(57) CLAIM

The ornamental design for a third brake light, as shown and described.

DESCRIPTION

FIG. 1 is a perspective view of a third brake light showing our new design;

FIG. 2 is another perspective view thereof;

FIG. 3 is a front view thereof;

FIG. 4 is a back view thereof;

FIG. 5 is a top view thereof;

FIG. 6 is a bottom view thereof;

FIG. 7 is an enlarged left view thereof;

FIG. 8 is an enlarged right view thereof; and,

FIG. 9 is a partially enlarged view of FIG. 3.

The broken lines shown on the drawings depict portions of the third brake light that form no part of the claimed design.
